Primary Examiner — Rachel A. Voorhies*Assistant Examiner* — Benjamin D. Wannemacher*(74) Attorney, Agent, or Firm* — Karin L. Williams; Alan D. Kamrath; Mayer & Williams PC(57) **CLAIM**

The ornamental design for a tool handle, as shown and described.

DESCRIPTION

FIG. 1 is a perspective view of a tool handle showing my new design;

FIG. 2 is a left view thereof;

FIG. 3 is a top view thereof;

FIG. 4 is an enlarged view of the portion of the left side of the tool handle shown in a dot-dash broken line circle indicated in FIG. 1; and,

FIG. 5 is an enlarged view of the portion of the left side of the tool handle shown in a dot-dash broken line circle indicated in FIG. 3.

The dash-dash broken lines depict portions of the tool handle in which the design is embodied that are not considered part of the claimed design. The dot-dash broken line circles depict the limits of the enlarged views and form no part of the claimed design. The dot-dash lead lines in FIG. 1 labeled 4 and in FIG. 3 labeled 5 indicate the areas from which the enlargements in FIGS. 4 and 5 are taken and form no part of the claimed design.
